UNITED STATES PATENT OFFICE.

ALAN ARMSTRONG, OF WHITLEY BAY, ENGLAND, ASSIGNOR TO PILKINGTON BROTHERS LIMITED, OF LIVERPOOL, ENGLAND, A COMPANY OF GREAT BRITAIN.

PRODUCTION OF WELDED WIRE FABRIC AND APPARATUS THEREFOR.

Application filed September 24, 1926, Serial No. 137,493, and in Great Britain October 3, 1925.

This invention has for its object a process and apparatus for the production of welded wire fabric in which two pluralities of wires are welded at their crossing points, each wire of one plurality being at an angle to each wire of the other plurality. Besides the above mentioned pluralities of wires, the fabric may contain other wires, such, for instance, as selvedge wires running in the direction of the length of the fabric.

According to the invention the wire from which the fabric is produced, is contained on a plurality of spools, and wires from said spools are brought into two closely adjacent planes, the wires in one plane being at an angle to those in the other plane, the wires of the two planes being welded together at their crossing points to form the fabric. Means are provided for feeding the fabric without injuring it, for varying the width of fabric produced, for incorporating selvedge wires in the fabric and for producing a plurality of narrow fabrics simultaneously.

In the accompanying drawings:—

Figure 1 is a side elevation of pertinent parts of the machine;

Figure 2 is a plan of Figure 1;

Figure 3 is a rear elevation of Figure 1 with parts omitted;

Figure 4 is a transverse section and Figure 5 a longitudinal section, both on an enlarged scale, of the mesh-forming device;

Figure 6 is a transverse section and Figure 7 portion of a front view, both on different enlarged scales, of the welding device;

Figure 8 is a side view, on an enlarged scale of a portion of one of the transfer spindles and its bracket;

Figure 9 is a side view of part of the gearing of the machine;

Figure 10 is a plan of part of the feed drum;

Figure 11 is an enlarged view of a portion thereof;

Figure 12 is a section along the line 12—12 of Figure 11, on an enlarged scale;

Figure 13 is a transverse section of the fabric drum;

Figure 14 is a front view of a portion thereof;

Figure 15 is a diagram of the wires at the welding lines;

Figure 16 is a detail view of one of the die operating cams, and

Figure 17 is a plan of detached parts of the mechanism.

Throughout this specification the front of the machine is regarded as that part towards which the wires of the fabric travel, viz.—the right-hand sides of Figures 1 and 2.

Referring to the drawings, 1 is the frame of the machine, 2 is an upstanding bracket thereon, supporting the rotating spool drum 3 and the transfer spindle brackets 4. The general action of the machine without considering details, is as follows:—Referring to Figure 1, the wires of which the fabric is formed, are contained on spools 3^a arranged in two circles around the periphery of the spool drum 3; only a few of these spools are shown in the drawing, but it is to be understood that there are as many of these spools as there are wires (other than selvedge wires) in the fabric. The spool drum 3 is arranged to turn on an annular extension (23) of the bracket 2. The wires 5 pass from the spools to two sets of mesh-forming carriers arranged in two horizontal rows, one immediately below the other, located between two transversely extending screws 6 and 7 (also in Figure 4). The wires 5, of which only two are shown in Figures 1 and 4, lie on a circle at the spool drum 3 and are brought to two closely adjacent horizontal planes between the screws 6 and 7. The wires in one plane when leaving the screws 6 and 7, cross those in the other plane, and pass to the welding dies in the beams 8 and 9, where they are welded together at their crossing points. From here the fabric passes to the feed drum 10 and from this to the fabric drum 11.

The operation of the machine will now be described in detail. The main driving shaft 12 (Figures 1 and 2) extending transversely of the machine, carries a spiral gear 13 driving a spiral gear 14 on the front end of a shaft 15 which, at its rear end, has fast on it a crank disc 16 working a connecting rod 17. This rod operates a pinion 18 (shown in dotted lines in Figure 1) through a set of change gear wheels 19, a ratchet wheel 20 and ratchet 21. The pinion 18 is not visible in Figure 2 but is on the centre line of the machine. This gearing may be of any ordinary construction and need not be more particularly described. The pinion 18 drives the spool drum 3 by a toothed ring 22 on the drum. The spool drum 3, which is a ring, is

rotatably mounted on an annular extension of the bracket 2, shown in dotted lines at 23 in Figure 1. A plate 24 is fixed to the front face of the spool drum 3 and has a plurality of holes, corresponding to the plurality of spools 3^a, through which the wires 5 pass.

Referring to Figures 4 and 5, the wires 5 pass to two series of carriers 25. Each carrier is, in section, a little less than a semi-circle in general form, with two lugs 26 serving to retain and guide it in the frame 1, and a central lug 27 which engages in the thread of the screw 6 or 7, by which it is driven. Each carrier is traversed by a longitudinal hole 28 through which the respective wire passes. The carriers are arranged in two series one above the other (Figure 5) the upper engaging by their lugs 27 with the screw 6 and the lower by their corresponding lugs with the screw 7. They are separated by a plate 29 along which they slide. The screw 6 turns clockwise, as viewed in Figures 1 and 4, causing the upper carriers to move from right to left, and the screw 7 counterclockwise, causing the lower carriers to move from left to right. By reason of this movement the wires passing through the upper and lower series of carriers 25 are caused to cross each other to form diamond-shaped meshes and are bent about the hereinafter described selvedge wires at the edges of the fabric. The rate of turning of the screws 6 and 7 is so related to the rate of turning of the spool drum 3, that a carrier completes its course across the machine in the time of half a turn of the spool drum.

The transfer device by which a carrier 25 of one series, which has reached the end of its course, is transferred to the other series will now be described. The extreme left-hand upper carrier in Figure 5 has passed off the plate 29 on to a tongue 30 which, in the position shown, forms a continuation of the plate 29. The tongue 30 forms a prolongation of a transfer spindle 31, of which there are two, one at each side of the machine (Figures 1, 2 and 8) running in brackets 4. The tongue 30 is not visible in Figure 4 because it lies behind the plate 29. The spindles 31 and brackets 4 are arranged to be adjustable horizontally transversely of the machine, but for the moment and for convenience, the brackets are regarded as fixed to the bracket 2. Each spindle 31 has fast on its rear end, a spiral gear 32 driven by a spiral gear 33 on a horizontal transverse shaft 34 running in a bearing 35 on the respective bracket 4 (Figure 8) and supported in other bearings 35^a (Figure 2), fast to the bracket 2. The shaft 34 is driven by an intermittent bevel gear, consisting of a wheel 36 on said shaft and a wheel 37 on the upper end of a vertical shaft 38. This shaft is driven by a pair of bevel gears 39 from the shaft 15. The main shaft 12, and with it the shafts 15 and 38, are turned continuously, but the shaft 34 and the transfer spindles 31 are turned intermittently by means of the intermittent bevel gear 36, 37. The gearing is so arranged that each transfer spindle 31 turns through 180 degrees, then remains stationary and then turns again through the remaining 180 degrees.

Referring again to Figure 5, after the screw 6 has turned so as to move the extreme left-hand carrier off the plate 29 on to the tongue, that is to say, into the position indicated in Figure 5, the spindle 31 receives its turning motion, and this brings the said carrier into an inverted position below the tongues 30 and in the lower series of carriers. A similar action takes place at the other end of the screws 6 and 7, the last carrier in the lower series being turned and brought into the upper series. By this means the carriers are given a circulating motion around the plate 29.

Referring now to the welding device shown in Figures 6 and 7, the lower beam 9, attached to the frame 1, carries two welding bars 38 insulated from the beam by a strip 39. The upper beam carries two series of welding dies 40 attached to rods 41 adapted to slide vertically in holes in the beam 8 and pressed downwards by springs 42. These dies 40 are staggered in the two series and co-operate with the welding bars 38. In Figure 7, the front series of welding dies 40 and rods 41 are omitted in order to make the drawing more clear; if they had been represented, they would appear in the spaces between the back dies which are shown. The electrical connections to these welding bars and dies, the transformers and switch device are not shown, as these may be of any form customary in welding machines, and said switch device may be operated from a gear or chain wheel 104 on the shaft 15.

The upper beam 8 is mounted on two rods 43 (Figures 1, 2, 6 and 7) adapted to slide vertically in suitable guides.

By mechanism hereinafter described, the rods 43 are depressed at the appropriate times so as to press the welding dies 40 on to the pairs of crossing wires which pass close above the welding bars 38, and effect a weld at each crossing point by pressing the wires on to the welding bars. In order to ensure the correct location of the wires and produce uniform meshes, a mesh-forming bar 44 is attached to the upper beam 8. On the right of Figure 7, some of the welding dies and their rods 41 are omitted to more clearly show the bar 44, which is provided with a V-notch 52 opposite each welding die of one of the rows 120 of such dies, the notch terminating in a slot 53. Co-acting with the mesh-forming bar 44 is a sliding bar 45, adapted to slide up and down on the beam 9. Lugs 46, one at each end of the bar 45, engage with arms 47 at 130

tached to a shaft 48 which is adapted to turn in brackets 49 on the beam 9. An arm 50 on this shaft is depressed at the appropriate times by mechanism hereinafter described, so as to raise the sliding bar 45. Figure 15 is a diagrammatic plan view of the welding dies 40, the mesh-forming bar 44 and the wires 5. From this it will be seen that the dies are so disposed as to weld three out of the four crossing points of each mesh 51, while the fourth crossing point is on the line of the mesh-forming bar 44. If then, the wires do not cross accurately along this line and along the lines of the welding dies, the V-notches 52 of the bar 44 embrace the pairs of wires when the beam 8 is depressed, and the wires are forced into the slot 53 by the bar 45, which is raised to meet the bar 44: the wires thus are forced to cross along the line of the bar 44 and thus ensures uniformity in the meshes.

The feed of the wires 5, and of the fabric when formed, is effected by the feed drum 10 and the fabric drum 11. The feed drum 10 is cut with two series of crossing spiral grooves 54 as shown in Figures 10, 11 and 12. In Figure 10 the grooves are indicated merely by lines; in Figure 11 they are shown on an enlarged scale, together with a circumferential groove 55, which is hereinafter referred to, while Figure 12 as hereinbefore described, is a section along the line 12-12 of Figure 11. The grooves 54 are so formed that the wires of the finished fabric can enter them. The feed drum 10 is rotated intermittently to feed the fabric, by a ratchet wheel 56 operated by a pawl 57 (Figures 1 and 9) pivoted to a lever 58 which is pivoted on the shaft 59 of the drum 10.

The fabric drum (Figures 13 and 14) is composed of two preferably sheet metal semi-cylinders 11 and 11^a held together by end pieces or straps in two portions 60 and 60^a, which can be pressed together by bolts and wing-nuts 61. The portions 60 are semi-anular except for the lugs to take the bolts and wing-nuts; the portions 60^a have plates, also identified by the reference 60^a, constituting end plates to the drums, as shown by the dotted lines in Figure 14. The fabric is attached to the drum by loosening the wing-nuts 61, inserting the end of the fabric between the semi-cylinders 11 and 11^a and then tightening the wing-nuts. Stub shafts 62 are attached to the end plates 60^a and turn in bearings in the frame 1. The stub shaft on the right hand end of the drum is provided with a clutch, see particularly Figure 14, consisting of a friction plate 63 and a driving plate 64, the latter fixed on a sleeve 65 and pressed against the friction plate and the plate 60^a by a spring 66. A chain wheel 67 is fixed to the sleeve 65 and is chain driven from a chain-wheel 68 (Figure 2) on the shaft 59 of the feed drum 10. The sizes of the two chain-wheels 67 and 68 are so related to the

diameters of the feed and fabric drums, that the latter tends to turn at a slightly higher peripheral speed than does the feed drum, when it is empty, the clutch 60^a, 63, 64 slipping sufficiently to compensate for the surplus motion of the fabric drum. By this means the pull required to feed the fabric and wires is taken mainly by the fabric drum.

The mechanism for operating the above described parts of the machine is shown in Figure 9, from which all framework and bearings have been omitted. The main shaft 12 has fixed to it a gear wheel 69, immediately behind the spiral gear 13, which is partly broken away to show it. The wheel 69 drives an equal wheel 70 on a shaft 71 and this drives an equal gear wheel 72 (shown in dotted lines) on a shaft 73. On the shaft 73 is fixed an intermittent gear wheel 74 which drives an intermittent gear wheel 75 on the screw 7, and on this screw is a gear wheel 76 (shown in dotted lines) which drives the gear wheel 77 on the screw 6. By means of the intermittent gears 74 and 75 and the gears 76 and 77 the screws 6 and 7 are turned to traverse the two rows of carriers 25 in respectively opposite directions and intermittently.

On the main shaft 12 and behind the gear wheel 69 is a disc 78 shown in detail in Figure 16, with a cam groove on its back face. A roller 79 on an arm or lever 80 engages the cam groove in the disc 78. The arm 80, at one end, is pivoted to the frame at 81 and, at its other end is pivoted at 82 to one rod 43 of the welding beam 8. The other rod 43 is correspondingly connected to a lever operated by a cam disc similar to 78, attached to the main shaft 12 at the other side of the machine. The cam groove in the disc 78 is so shaped as to depress the beam 8 and close the welding dies at the appropriate time, and retain them closed for the requisite period. Pivoted also at 82 is a rod 83 connected with the lever 50, which, as before described, operates the shaft 48 and the bar 45, through the arm 47 and lugs 46. The bar 45 is thereby raised as the beam 8 is depressed. On the wheel 70 is secured an eccentric disc 84 with strap 85 and connecting rod 86 pivoted at 87 to the pawl-operating lever 58.

In order to provide selvedge wires in the edges of the fabric, the transfer spindles 31 and their tongues 30 are provided with axial holes 88 (Figures 5 and 4). Selvedge wires are passed through these holes from spools 89 (Figures 1, 2 and 3) mounted on a strip 90 fast on the bracket 2. As shown in Figures 10 and 11, circumferential grooves 55 aligned with crossing points of the mesh wires 5, are provided in the feed drum 10 to take these selvedge wires.

The machine is arranged so that fabric of a width less than the maximum can be formed, and also so that two or more strips

of fabric, each with its selvedge wires can be formed simultaneously, provided that the total width of the strips does not exceed the maximum width of fabric, for which the 5 machine is constructed.

To vary the width of the fabric to be produced, the transfer spindles 31 are made adjustable in position. Figure 8 shows the left-hand end of the bracket 4 of one of the 10 transfer spindles 31, the view being the same as in Figure 1, but drawn to a larger scale. The bracket is adapted to slide in guide ways 91, in the bracket 2. A right and left handed screw 92 journaled in the bracket 2, as shown 15 in Figure 1, traverses nuts 93 in the brackets 4, that in one bracket being right-handed and that in the other left-handed. By turning the screw 92, the two brackets 4 with their transfer spindles 31 can be brought and 20 retained nearer together. The spiral gear wheels 33 are mounted on the shaft 34 on sliding feathers and are caused to slide along the shaft as the brackets 4 are moved, by the bearing pieces 35. A plurality of selvedge 25 wire circumferential grooves 55 are provided on the feed drum 10 as shown in Figure 10, and the machine can therefore be operated with the transfer spindles 31 in positions opposite to any of the grooves. The selvedge 30 wire spools 89 are placed in corresponding positions on the strip 90. Now, when the transfer spindles are not at their extreme positions, a certain number of the carriers 25 must be removed and a plate 29 shorter in 35 transverse length, must be used. This is conveniently arranged by making the plate in two separable parts (as shown in Figure 17) which, for the minimum width of fabric, 40 mutually engage with each other at their inner ends, and for greater widths of fabric engage with the respectively opposite ends of one of a series of interchangeable plate members 29^a of respectively different lengths.

As shown best in Figure 17, the plate 29 or 45 each section thereof, has a lug 94 adapted to enter a slot in a projection 95 from each bracket 4 and be fixed therein. In order that the carriers 25 may be able to be turned by the tongues 30, slots 96 (shown in dotted 50 lines in Figure 5) are cut in the threads of the screws 6 and 7 in such positions that, when the tongues 30 are turning, the lugs 27 of the carriers 26 are in the slots of the screws 6 and 7 which then are stationary.

When it is desired to produce two strips of fabric simultaneously, a shearing device of any convenient construction is fitted to the machine to cut the whole width of fabric into two strips. Such shearing device may 55 consist of two shafts 97 and 98 (Figures 1 and 2) carrying circular knives 99, the shaft 97 being driven from the feed drum shaft by a chain gear 100 and the shaft 98 being driven from the shaft 97 by gears 101. In order 60 that the two strips of fabric so formed, may

have selvedge wires at both edges, two spools of wire 102 (Figures 2 and 3) are attached to the strip 90 in such position that the line of division of the fabric lies between them. Wires are taken from these spools through 70 holes in the plate 29, as at 103, (Figure 5) and pairs of grooves 104 (Fig. 10) are formed in the feed drum to accommodate the wires. The whole width of fabric may be formed into more than two strips by the provision of further pairs of shearing knives 99 and further selvedge wire spools. 75

The operation of the machine is as follows:—

The ratchet lever 58 of the feed drum 10 is 80 operated by the rotation of the eccentric 84 to feed forward the fabric, the fabric drum 11, 11^a, and (if used) the shearing device 99 rotating with the feed drum. Simultaneously the spool drum 3 rotates through a distance 85 equal to the pitch of its spools 3^a. Simultaneously also the screws 6 and 7 are rotated to move the carriers 25 through a distance equal to their pitch, the upper ones to the left and the lower to the right. Then, during the 90 backward movement of the ratchets 57 and 21, and by means of the intermittent gears 74, 75, the feed of the fabric, the rotation of the spool drum 3 and the movement of the carriers 25 all cease. The cam grooves on the discs 78 95 acting through the rollers 79, levers 80 and rods 43, then cause the upper welding die beam 8 to descend and press the mesh and selvedge wires against the lower welding dies and simultaneously the bar 45 rises, through 100 the action of the lever 47, 50, and connecting rod 83, to co-act with the mesh-forming plate 44 to locate the wires accurately. The welds are then effected. At the end of the welding operation and by means of the intermittent 105 bevel gear 36, 37, the transfer spindles 31 are turned through 180 degrees to transfer the end carriers 25 from one series to the other series of carriers. After this operation the welding dies are opened sufficiently to free the 110 wires. The cycle of the machine is then complete.

When a fabric of less than full width is to be produced, for instance a fabric of half full width, half the carriers 25 must be removed, 115 half the spools on the drum 3 must be removed, or left idle, the transfer spindles 31 must be moved towards each other to half the maximum distance apart, and the change speed gears 19 of the spool drum must be 120 changed to give said spool drum twice the speed, so that it makes one revolution while any one carrier 25 completes its cyclical course.

The machine described above is only one form of many possible devices for carrying out the invention, the essential feature of which is that two pluralities of wires are juxtaposed, each wire of one plurality being at an angle to each wire of the other plurality, thus providing a plurality of points where 125 130

the wires of the two pluralities cross and where they are welded.

If desired, the selvedge wires may be crimped by passing said wires between pairs of crimping rollers, so as to ensure their remaining in correct position.

It will be obvious that the before described machine may be arranged to produce fabric which meshes of shape other than the diamond shape depicted in the drawings, for example, said meshes may be of square form ranged angle-wise across the fabric, as when each wire of one plurality is at an angle of 90° to each wire of the other plurality, the only material changes in the machine necessary for such variations, being a substitution for one feed drum, of another having the desired lay-out of grooves 54, and a variation in the relative speeds of operation of the different organs of said machine.

Having described my invention, I declare that what I claim and desire to secure by Letters Patent is:—

1. Process of producing a welded wire fabric by supplying simultaneously all the wires (except selvedge wires) going to form the fabric, bringing half of said wires into one plane and the other half into a closely adjacent plane, the wires in the two planes crossing each other, and welding together the wires in the two planes at their crossing points.
2. Process of producing a welded wire fabric by supplying a plurality of wires, moving the wires of the said plurality cyclically, bringing half the wires thereof into one plane and the other half into a closely adjacent plane, the wires in one plane being at an angle to the direction of length of the fabric and the wires in the other plane being at an equal but opposite angle to said direction, and welding together the wires in the two planes at their crossing points.
3. Process of producing a welded wire fabric by supplying a plurality of wires, moving the wires of the said plurality cyclically, bringing half the wires thereof into one plane and the other half into a closely adjacent plane, feeding the wires by a motion compounded of a motion in the direction of the fabric and a motion transverse to the fabric, the wires in the two planes crossing each other, and welding together the wires in the two planes at their crossing points.
4. Process of producing a welded wire fabric by supplying a plurality of wires, moving the wires of the said plurality cyclically, bringing half the wires thereof into one plane and the other half into a closely adjacent plane, the wires in the two planes crossing each other, and welding together the wires simultaneously along two lines of their crossing points extending transversely to the fabric.
5. Process of producing a welded wire fabric by supplying a plurality of wires, moving the wires of the said plurality cyclically, bringing half the wires thereof into one plane and the other half into a closely adjacent plane, the wires in the two planes crossing each other, welding together the wires in the two planes at their crossing points, running selvedge wires in the direction of the length of the fabric and bending the wires of the plurality round the selvedge wires.
6. Process of producing a welded wire fabric by supplying a plurality of wires, moving the wires of the said plurality cyclically, bringing half the wires thereof into one plane and the other half into a closely adjacent plane, the wires in the two planes crossing each other, running wires in closely adjacent pairs in the direction of length of the fabric, welding at crossing points the wires of one plane to those of the other plane and the wires of each plane to the said wires in pairs, and cutting the fabric between the two wires of each pair to form a plurality of strips of fabric.
7. Process of producing a welded wire fabric by supplying simultaneously all the wires (except selvedge wires) going to form the fabric, from spools on a drum, rotating the drum, bringing half of the said wires into one plane and the other half into a closely adjacent plane, the wires in the two planes crossing each other, and welding together the wires in the two planes at their crossing points.
8. Process of producing a welded wire fabric by supplying a plurality of wires, moving the wires of the said plurality cyclically, bringing each wire to one of a plurality of carriers disposed in two closely adjacent planes, moving the carriers cyclically along each plane and into the other plane, the wires passing to the carriers in one plane being thereby caused to cross those passing to the carriers in the other plane, and welding together the wires at their crossing points.
9. In the process according to claim 8, adjusting the speed of cyclical motion of the wires and that of the carriers so that the two motions complete their cycle in the same time.
10. Process of producing a welded wire fabric by supplying a plurality of wires, moving the wires of the said plurality cyclically, bringing each wire to one of a plurality of carriers disposed in two closely adjacent planes, moving the carriers cyclically along each plane and into the other plane, the wires passing to the carriers in the other plane, running wires in the direction of length of the fabric between the carriers in the two planes, and welding together the wires at their crossing points.

In witness whereof I have affixed my signature hereto.

ALAN ARMSTRONG.
